COLLAPSIBLE TRAILER

Klaus E. B. Krutzikowsky, 4331 Lowell Ave.,
Chicago, Ill. 60641

Filed Feb. 4, 1966, Ser. No. 916

Term of patent 14 years

(Cl. D14—3)

FIG. 1

FIG. 2

FIG. 3

FIG. 4

FIG. 1 is a perspective view of a collapsible trailer;
FIG. 2 is a side elevational view of the trailer;
FIG. 3 is a top plan view of the trailer; and
FIG. 4 is a rear elevational view of the trailer.
The hidden side is identical to the side shown.

The dominant features of the design reside in the solid line disclosure wherein the sidewalls are further characterized by the blended concave to convex to concave contouring and the downwardly sloping sidewall profile.

I claim:

The ornamental design for a collapsible trailer, as shown and described.
